RADIATOR

Elbert O. Haskins, Rutherford, and Thurlow W. Reynolds, Woodridge, N. J., assignors to American Radiator Company, New York, N. Y., a corporation of New Jersey

Application January 13, 1932. Serial No. 586,358

4 Claims. (Cl. 257—159)

Our invention relates to new and useful improvements in radiators, and more particularly to an inlet nipple or bushing embodied in the radiator.

5 In the heating of radiators by steam, it frequently occurs that the water of condensation which collects at the bottom of the radiator will cause water hammer when steam is admitted to the cold or cool radiator, and the water hammer is more pronounced and certain of occurring 10 in a radiator having the steam inlet at an upper end nipple opening and a trap controlled outlet at the opposite lower end. It is also common for the radiator heated by steam to trap air, i. e., 15 for a pocket of air to collect in that portion of the radiator which is below the steam inlet and which causes inefficient and unequal heating of the radiator. It is therefore one object of our invention to provide a radiator in which water hammer and the trapping of air will be eliminated.

The invention consists in the novel construction and combination of parts, to be more fully described hereinafter, and the novelty of which 25 will be particularly pointed out and distinctly claimed.

In the accompanying drawing, to be taken as a part of this specification, we have fully and clearly illustrated a preferred embodiment of our invention, in which drawing—

Figure 1 is a view in front elevation of a radiator showing in dotted lines the inlet nipple or bushing member in operative position;

Fig. 2 is a detail view in section on the line 35 2—2 of Fig. 1, and

Fig. 3 is a view in perspective of the nipple or bushing member.

Referring to the drawing by characters of reference, 1 designates generally a hollow heating 40 radiator comprising a plurality of vertical columns or tubes, preferably of cast iron, and which is preferably formed of a plurality of separate hollow sections 2 joined together by and inter- 45 communicating through the bores 3 of aligned top and bottom hollow nipples 4. Coaxial with the top nipple bores 3 there are aligned apertures 5, 6 through the end walls of the radiator, the aperture 5 being closed and sealed by a plug member 7. At the bottom of the radiator in the end 50 walls thereof, there are apertures 8, 9 aligned with the bottom nipple bores 3, the aperture 9 which is beneath and at the same end of the radiator as aperture 6, being closed and sealed by a plug member 10.

55 The aperture 6 has secured and sealed therein

a nipple or bushing member 11, preferably of cast iron, which extends substantially across the width of the first or inlet column or section. The member 11 is preferably in the form of a hollow plug having a substantially cylindrical body portion 12 and a substantially cylindrical internal chamber or bore 13, which is closed at its inner end by a wall 14 normal to the axis of the bore, and which at its other or outer end has an internally threaded inlet port 15 to receive a steam supply pipe or conduit member. The portion 12 is externally screw threaded, as at 16, for a part of its length adjacent its outer end for threaded engagement with internal threads in aperture 6. The outer end of member 11 may be provided 60 with a polygonal portion 17 to accommodate a wrench or the like. Transversely through the wall of portion 12, there are a plurality of transverse apertures 18, preferably four in number, substantially equally spaced circumferentially 65 from each other and being in a plane through the vertical center line of the inlet column and transverse to the axis of the inlet 6. The apertures 18 are preferably positioned longitudinally of member 11, such that they will be substantially 70 midway of the end to end width of the hollow inlet column. Through the end wall 14 is an aperture 19, preferably coaxial with the top nipple bores 3, so as to deliver a stream or jet of steam across the top of the radiator, and which 75 is preferably of less area than the area of an aperture 18, for example, apertures 18 may each be of one-quarter inch diameter and aperture 19 of one-eighth inch diameter.

The operation of the radiator is as follows: 80 The radiator is connected in a steam line, the steam supply pipe 20 being threaded and sealed in the bushing aperture 15, and the outlet aperture 8 being connected to an automatic trap 21, such, for example, as the well known type having a thermostatically operated valve, the trap in turn being connected to the return line or pipe 22. When steam is supplied to a cold or cool radiator which is not provided with a bushing member 11, substantially all of the admitted steam 85 flows across the top of the radiator through the aligned top apertures 3 and down the furthermost end or outlet column, as indicated by the arrows M, with a small portion of the steam supply splitting off and flowing down the intermediate sections, as indicated by the arrows S. The result 90 of this action is that the steam flowing down the outlet end column to the outlet 8 heats the thermostatic trap, thus closing the trap valve before the air is driven out of the radiator. The en- 95

trapped air pockets in the lower portion of the radiator beneath the steam inlet 6, and generally beneath some such line as is indicated by A—A. Also when the bushing member is not employed, 5 the steam may on closing the trap flow through the lower nipple bores toward plug 10 and drive the condensate or water in the bottom of the radiator ahead of it, thus causing a severe water hammer at the bottoms of the inlet columns. 10 When the radiator is provided with a bushing member 11, in accordance with our invention, the volume of steam directed internally across the top of the radiator is greatly reduced by the aperture 19 and the greater portion of the steam 15 admitted to the plug member passes through apertures 18 radially into the inlet section or column. As a result, most of the steam admitted to the bushing passes downward in the first or inlet column and then horizontally through the 20 bottom openings 3, as indicated by the arrows x. As the steam passes through each of the bottom openings, a quantity of the steam will split off and rise in each column, as indicated by the arrows y, it being apparent that the upflowing 25 quantities will taper off from the inlet column toward the outlet column. It will thus be seen that the air pocket under line A—A is eliminated, the steam which rises in the respective 30 intermediate columns carrying the air upward before it into the path of the jet M, which serves to sweep the air into and down the end outlet column, so that the air in the radiator is driven out ahead of the steam and before the steam reaches the trap 21. Elimination of water hammer 35 is also accomplished, because, as will be seen, the greater part of the admitted steam is moving through the bottom nipple openings 3 toward the outlet 8, and therefore acts to drive the water ahead and into line 22 through the 40 open trap. Due to the elimination of the condensate and the air, the radiator will heat uniformly throughout its area, so that the bushing member 11 causes an equalization in the heating up of the columns. 45 What we claim and desire to secure by Letters Patent of the United States is:—

1. In a steam heating radiator comprising a plurality of columns having aligned top and bottom openings for intercommunication between 50 said columns, and in which one of the end columns has a steam inlet opening in line with said top openings, a substantially cylindrical member sealed in said inlet opening and extending into the radiator, said member having a substantially cylindrical bore, said bore being open at its outer 55 bend and threaded to receive a steam supply conduit, and a wall member closing the inner end of said bore and having an aperture therethrough substantially coaxial with said top openings, said

60 cylindrical member having an aperture through

65

70

the side wall thereof substantially in the vertical longitudinal center line of said one end column, whereby steam issuing from said second-named aperture will pass downward in said end column and thence upward in the intermediate columns to heat the radiator uniformly. 80

2. In a steam heating radiator comprising a plurality of vertical intercommunicating hollow columns communicatively connected by aligned steam flow openings adjacent their tops and bottoms, and having one of the end columns provided with a steam inlet opening aligned with the top openings, a substantially cylindrical member sealed in said inlet opening and extending into said one end column and substantially thereacross, said member having a cylindrical bore open at its outer end for connection to a steam supply conduit, and a wall member closing the inner end of said bore and having an aperture therethrough substantially coaxial with said aligned top openings, said cylindrical member having a plurality of apertures therethrough in a plane normal to the bore of said inlet opening and substantially in the vertical center line of said one end column. 90

3. In a steam heating radiator comprising a plurality of columns communicatively connected by aligned top and bottom flow openings and in which one of the end columns has an inlet opening in line with said top flow openings, a hollow plug member sealed in said inlet opening and extending into the radiator, the outer end of said plug member being adapted for connection to a supply conduit to supply steam to the interior of the plug, the inner end of said plug member extending into the radiator in line with said top openings and having an aperture delivering steam through said aligned top openings toward the opposite end column, and said plug member having an aperture through its side wall for delivering steam into said one end column. 100

4. In a steam heating radiator comprising a plurality of columns communicatively connected by an aligned top and bottom opening and in which one of the end columns has a steam inlet opening in line with said top openings, a substantially cylindrical member sealed in said inlet opening and extending into the radiator, the inner end of said member being located in said one end column, said member having a substantially cylindrical bore opening at its outer end for connection to a steam supply conduit, and said member having a transverse wall closing the inner end of said bore and having an aperture therethrough substantially coaxial with said top openings, and said member having an outlet aperture through its side wall for delivering steam radially of said member into said one end column. 110
